(57) **CLAIM**

The ornamental design for a fuse, as shown and described.

DESCRIPTION

FIG. 1 is a front perspective view of a fuse showing our new design;

FIG. 2 is a rear perspective view thereof;

FIG. 3 is a front view thereof, the rear view being a mirror image thereof;

FIG. 4 is a right side view thereof;

FIG. 5 is a left side view thereof;

FIG. 6 is a top view thereof;

FIG. 7 is a bottom view thereof;

FIG. 8 is a cross-section view taken along line 8-8 in FIG. 3; and,

FIG. 9 is a cross-section view taken along line 9-9 in FIG. 4.

The broken lines in the drawings illustrate features of a fuse that are not being claimed, and form no part of the claimed design. The dash-dot broken lines show the boundary of the claim and form no part of the claimed design.
